(57) **CLAIM**

The ornamental design for an earphone with charging case assembly, as shown and described.

DESCRIPTION

FIG. 1 is a top, front, left side perspective view of a charging case of an earphone with charging case assembly, shown separately for ease of illustration and in an open state; FIG. 2 is a bottom, rear, right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a top, front, right side perspective view of an earphone of the earphone with charging case assembly, shown enlarged for clarity of disclosure; FIG. 10 is a bottom, rear, left side perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a top, front, left side perspective view of the earphone with charging case assembly, shown in use with the earphone received in the charging case; and, FIG. 18 is a top, front, left side perspective view of the charging case of the earphone with the charging case assembly is in a close state.

The broken lines on the earphone and charging case depict portions of the earphone with charging case assembly that form no part of the claimed design. In FIG. 17, the broken lines showing an additional earphone depict environment and form no part of the claimed design.

1 Claim, 18 Drawing Sheets
